UNITED STATES PATENT OFFICE

EMIL S. DENK, OF VILLA PARK, ILLINOIS

ATTACHING MEANS FOR TILE

Application filed May 25, 1927. Serial No. 193,967.

This invention relates to attaching means and more particularly to a type adapted to attach two members by means of a deformable element carried by one of said members and cooperating with means on the other of said members, said means deforming said first means, whereby an interlock between the two members is effected, the deforming operation being accomplished by the movement 10 of one of said members into the position in which it is desired to secure it.

My invention accordingly has very important uses and is particularly adapted for use as attaching means for elements such as 15 tiles, to a wall, ceiling or other plane surface where a space is provided for the tile or other means, which space is of a size only sufficient to receive the tile or element, so that the connecting operation must be 20 effected by moving the tile or element directly inwardly toward the wall.

My invention also has utility in attaching elements to plane surfaces such as panels or the like, whereby the securing means will 25 be entirely concealed by the panel itself, and the panel or other element will be held flush with and tightly against the plane surface.

It is the principal object of my invention 30 to provide an attaching means which will accomplish these features and to provide a means which is cheap, simple in construction and efficient in operation.

These and other objects are accomplished 35 by means of the arrangement disclosed in the accompanying sheets of drawing, in which—

Figure 1 is a perspective view of one application of my invention showing a plurality of tiles attached to a vertical wall.

Figure 2 is an enlarged horizontal showing of a cross sectional view taken on line 2—2 of Figure 1.

Figure 3 is a side elevation as seen on line 3—3 of Figure 2.

Figure 4 is a perspective view of one of the wall strips and the deformable attaching means connected thereto.

Figure 5 is a perspective view similar to Figure 4 showing a tile in mounted position.

Figure 6 is the blank stamped from sheet

metal from which tiles constructed in accordance with my invention are made.

Figure 7 shows the finished tile having the attaching flanges bent at right angles to the main face thereof.

Figure 8 is a perspective view of an end 65 of a bedstead showing a main panel and a detachable panel connected by means of a device constructed according to my invention.

Figure 9 is a similar view showing the deformable attaching means before the detachable panel has been placed in position.

Figure 10 is a rear view of the panel showing 60 its internal construction.

The various novel features of the invention will be apparent from the following description and drawings and will be particularly pointed out in the appended claims.

Referring to the drawing, particularly to 70 Figures 1 to 7 inclusive, it will be noted that my invention is illustrated in connection with the plurality of tiles 10, carried by a wall represented by a plurality of studs 11, positioned in spaced relation and having carried thereon deformable metal brackets 12, attached by any suitable means such as nails 75 13.

The tiles it will be noted, by referring to 80 Figure 6, are made from sheet metal blanks 14, having side wing portions 15 provided at their edges with arcuate slots 16 positioned in a manner to cooperate with wings 17 on the deformable brackets 12. The blanks as shown in Figure 6 are bent along 85 lines 18 to form a tile as shown in Figure 7, which presents an outer face 19 which is enameled in a desired manner to form a tile. Tiles thus formed are placed in a manner to overlie the brackets 12 so that the upper and lower flanges 15 are located substantially 90 midway of the bracket as shown in Figure 3, so that the wings 17 of the brackets are caused to fit within the straight portion of the arcuate slot 16. In this position the tiles 95 are thrust directly inwardly toward the walls which movement causes the wing 17 to be bent by the camming action of the walls of the arcuate slot, contacting the leading edge of the wing so that the wings and tile 100

flanges assume the interlocked position shown in Figure 5.

By referring to Figures 8 to 10 inclusive, it will be noted that my invention may be applied for the attachment of means other than tiles, such as for instance, the panel 20 applied to the main panel 21 forming the portion of the bedstead and designated generally 22. It is desirable in instances of this kind, especially in the case of metal beds to provide means for detachably securing the panel 20 without the necessity of drilling or providing bolt ends or other securing means which will project from the inner 15 surface of the bed and consequently present rough and sharp points or edges to engage and damage the bed clothes. In this instance the deformable brackets 23 may be attached as shown in Figure 9 by spot welding and presenting the wing portions 24 at right angles to the plane of the main panel of the bedstead.

The detachable panel is constructed as shown in Figure 10 with the four flanges 25 forming the edges and the internal ribs 26 connected by means of the ends 27 welded to the flanges 25 and provided with slots 28 similar to slots 16 provided in the flanges of the tile shown in Figure 6. The panel 30 thus constructed is positioned over the deformable brackets 23 on the bedstead end so that the wings 24 will be positioned at the mouth of the slots 28 and in this position the panel is forced inwardly in a manner to cause the arcuate slots 28 to effect a bending or deformation of the wings, so that an interlock will be effected to hold the panel in place, the deformation occurring by virtue of the movement of the panel 35 directly inwardly into the position in which it is to be secured.

In operation it will be readily understood, that in applying my invention to the application of tiles, that it is equally well adapted to apply tiles to the ceiling, walls or floors as desired and that instead of a plurality of individual deformable brackets these may be made from a single piece supplied in the form of a long strip whereby 50 accurate spacing of adjacent pairs of wings will be assured.

It is also within the scope of my invention to apply to the walls, a flexible strip bearing marks of suitable character to indicate the positions where the brackets 12 are to be secured in order to assure proper spacing for the reception of tiles.

By referring to Figure 3, it will be noted that each bracket 12 secures two flanges, 60 namely, the top flange of one tile and the bottom flange of the tile next above which necessitates that the top of one tile and the bottom edge of the one next above be applied at the same time. The matter of installing tiles, therefore, is that the bottom

of the first tile is applied first and the top of this tile is subsequently applied simultaneously with the application of the bottom of the tile next above.

It is obviously immaterial whether or not the studs 11 as shown in Figure 1 are used or whether solid wall is used as a securing surface for the brackets and it is also immaterial whether or not the brackets 12 be vertically disposed, one above the other or placed in a horizontal relationship, the only important feature being that they be positioned relative to each other in a manner to receive the tiles to give a complete smooth surface as shown in Figure 1.

Attention is directed to the fact that the arcuate slots 16 are provided on all four sides of the tile so that the manner of application is immaterial, it being the same irrespective of which side is presented upwardly.

The application of the detachable panels shown in Figure 10 to the end of the bedstead is substantially similar to that described in connection with the application 90 of the tiles, it merely being necessary to place the panel in its position slightly spaced from the plane of the main panel and force it directly inwardly in close engagement therewith.

Attention is directed to the fact that in the case the panel is used, the length of the wings 24 and the cooperating slots is such that a substantial interlock is effected when the panel is brought flush with the 100 plane surface to which it is attached.

My invention is especially useful as applied to the application of tiles, in that the interlock is effected by movement directly inwardly toward the surface to which the 105 tile is to be attached, consequently, a tile may be moved into an opening which is of a size just sufficient to receive it and the movement of the tile into such a position will cause deformation of the attaching bracket to effect the interlock and holding 110 of the tile in the position in which it is to be secured.

When it is desired to detach elements connected according to my invention, it is merely necessary to pull them outwardly in a direction opposite to that of installation and with sufficient force to straighten the attaching wings. It is my intention to cover the manner of attaching two elements, 120 irrespective of their nature and I have described my invention in connection with the installation of tiles and panels merely by way of illustration.

I claim:

1. A device of the character described comprising a surface and an element to be attached against said surface, and a deformable means projecting from said surface, means inside of said element having por-

tions cooperating with said deformable means to form a positive interlock therebetween, by deforming said transformable means beyond its elastic limit when said element is caused to approach said plane surface in a direction perpendicular thereto.

5 2. Means for attaching tiles comprising a plurality of definitely spaced deformable wings attached to a plane surface and slotted flanges on the tiles cooperating with said wings, said slotted flanges deforming said wings beyond their elastic limit to form a positive interlock upon movement of said tile into position.

10 15 3. In combination a surface, and a plurality of tiles adapted to be secured to said surface, means for securing said tiles comprising a plurality of spaced deformable wings extending from said surface, flanges on said tiles, provided with arcuate slots for cooperation with said wings and for deforming said wings upon movement of said tiles to attached position.

15 20 25 4. In combination a surface, and a plurality of tiles adapted to be secured to said surface, means for securing said tiles comprising a plurality of spaced deformable wings extending from said surface, flanges on said tiles, provided with arcuate slots for cooperation with said wings and for deforming said wings upon movement of said tiles to attached position, each wing element cooperating with adjacent flanges of adjacent tiles.

25 30 35 40 45 5. In combination, a surface and an element adapted to be secured to said surface, and means for securing said element in attached position, comprising deformable means secured to said surface and an irregularly shaped slot in said element, said slot cooperating with and deforming said deformable means for securing said element, and said deformable means and slot being located between said surface and the outside of said element whereby a concealed attachment is provided.

Signed at Villa Park, Illinois, this 19th day of May, 1927.

EMIL S. DENK.
